(57) CLAIM

The ornamental design for a garment, as shown and described.

DESCRIPTION

FIG. 1 is a front, left perspective view of a garment showing the present design;

FIG. 2 is a front view thereof;

FIG. 3 is a left view thereof;

FIG. 4 is a right view thereof; and,

FIG. 5 is a back view thereof.

The evenly spaced broken lines shown in the drawings are directed to environment, are for informational purposes only, and form no part of the claimed design.

The dash dot broken lines depict boundaries of the claim that form no part of the claim.

The surface shading on the claimed portion is provided only to indicate the character and/or any contour or curvature of the surfaces.

1 Claim, 3 Drawing Sheets

FIG. 2

FIG. 1

FIG. 4

FIG. 3

FIG. 5
